UNITED STATES PATENT OFFICE.

WILLIAM H. BELL, OF ALLENTOWN, PENNSYLVANIA, ASSIGNOR TO EDWARD GATELY AND THOMAS M. FITZGERALD, OF PHILADELPHIA, PENNSYLVANIA.

DESIGN FOR A RUG.

SPECIFICATION forming part of Design No. 32,559, dated April 17, 1900.

Application filed March 14, 1900. Serial No. 8,678. Term of patent 7 years.

To all whom it may concern:

Be it known that I, WILLIAM H. BELL, a citizen of the United States, residing at the city of Allentown, county of Lehigh, State of Pennsylvania, have invented and produced a certain new and original Design for a Rug, of which the following is a full, clear, and exact description, reference being had to the accompanying drawing, forming a part of this specification.

My invention relates to the surface ornamentation of a rug; and it consists of the design therefor shown in the accompanying drawing.

It consists of an oblong pattern the distinguishing features of which are a central figure composed of five hands grasped by each other, a representation of a car in one corner, a representation of a locomotive-engine and tender in another corner, a representation of a telegraph-operator and operating-table in another corner, and a representation of a railroad-track and telegraph-line in another corner, the several corner figures being surrounded with ornamental scroll-lines, and below the central figure are leaves and buds of a floral design filling the lower portion of the field-center.

I claim as new—

The design for a rug substantially as shown and described.

In testimony whereof I have hereunto affixed my signature this 10th day of March, A. D. 1900.

WILLIAM H. BELL.
